UNITED STATES PATENT OFFICE.

OSCAR ANTON BRUNLER, OF GLASGOW, SCOTLAND.

APPARATUS FOR STEAM-GENERATING AND SOLUTION-HEATING PURPOSES.

Application filed March 30, 1923. Serial No. 628,842.

To all whom it may concern:

Be it known that I, OSCAR ANTON BRUNLER, a citizen of the German Republic, residing at 140 West Graham Street, Glasgow, Scotland, North Britain, have invented certain new and useful Improvements in Apparatus for Steam-Generating and Solution-Heating Purposes, of which the following is a specification such as will enable others skilled in the art to which it appertains to make and use the same.

This invention relates to apparatus for generating steam or heating chemical solutions and is of that kind in which a burner is so positioned in relation to water or other fluid that the flame from the burner is immersed in the fluid.

The invention consists more particularly in improved means for igniting the burner and in the construction of the burner.

I will describe the invention more particularly as a steam generator but it must be understood that the apparatus can be employed for heating chemical solutions and other liquids.

According to the invention I construct the burner so that when the apparatus is to be started a bypass to the burner is first heated by a lamp or equivalent, say a blow lamp, and after this bypass or auxiliary burner is sufficiently hot the fuel is turned on to it and will heat up the main burner and ignite the fuel therein when it is turned on to the main burner, said main burner being preferably water cooled as hereinafter described.

Two forms of the invention are illustrated in the accompanying drawings in which:—

Fig. 1 shows substantially the whole apparatus in one form with the generator outside the storage tank for the steam and water supply.

Fig. 2 shows a detail of the burner and is substantially a section on line 2—2 of Fig. 1.

Fig. 3 shows another form of the apparatus with the generator inside the steam holder.

In Fig. 1 a holder or container 1 is adapted to receive the steam from pipe 2, having valve 3, in its upper part whilst the lower part serves as a storage tank to supply hot water through pipe 4 with valve 5 to the burner, the said water coming from

any suitable source through the pipe 6. All these parts are of substantially known form.

Adjacent to the container 1 is the generator which comprises a boiler *a* in which is fitted burner *b* supplied with any suitable fuel from pipe *c* said boiler having a draining or cleaning hole at *d*.

On the upper side of the boiler *a* is a tube-like part *e* provided with a removable metal cover *f* under which is a fireclay or equivalent lining cap. Within the part *e* is a fireclay or other suitable tube *g* directed downwardly towards the central portion *h* of the burner *b* and leading to passages *j* which have a common outlet *k* forming the burner proper. A hole *i* is formed through the part *h*, see Fig. 2 and is open to the water in the generator. The passages *j* are shown of flat form in Fig. 2 but any suitable shape may be employed.

A fuel bypass tube *c'* leads from the tube *c* to the inside of the part *e*. In practice I proceed substantially as follows when starting the apparatus. With the fuel cocks 80 turned off I remove cover *f* and the cap under same and introduce the flame of a lamp into the part *e* so as to heat the tube *g* to red heat. The cap and cover are then replaced and the cock in pipe *c'* opened 85 thus admitting fuel (fuel and air) to the tube *g* which combustible mixture ignites, or this ignition may take place before the cap and cover are replaced but when these are in position the flame at *g* is forced down 90 into the burner *b* and heats the bridge or part *h*. This burner may be of cast steel and the part *h* gets so hot after a few minutes that upon opening the cock in pipe *c* the fuel and air passing into the burner 95 ignite, and the flame passes at its highest temperature through the outlet *k*. When this has taken place the admission of fuel and air to the ignition lamp may be reduced or shut off. The air is forced into 100 the ignition lamp and the burner at a higher pressure than the steam pressure, by means of a compressor, (not shown), and the fuel is admitted at a higher pressure than the steam pressure, through the use of any suitable means. When the main flame burns, water is supplied to the generator from the container. The feed water is pumped into the container.

The apparatus will work with very little, 110

if any, attention for a long period providing the fuel and water supplies are maintained.

It will be understood that as steam mixed with combustion gases passes out of the generator by the pipe 2, water enters the generator through pipe 4. The presence of steam in the container brings the water to a temperature near boiling point and it is forced close to the flame thus insuring complete combustion.

In Fig. 3 the burner *m* is immersed in water in the boiler *n* which is positioned within the steam container or tank *o*. Openings *p* are provided for the steam above the level of the water in the boiler said water being supplied from any suitable exterior source through the pipe *q*.

Draining tubes are indicated at *r* and *s* and the steam pipe from the container is at *v*, whilst *t* and *u* are substantially the equivalents of the parts *f* and the supply to the main burner as in Fig. 1. Gauges and other usual instruments or fittings are fitted as may be required.

What I claim is:—

1. A liquid heater comprising a casing open to a liquid supply and having an outlet, a burner arranged in the casing below the outlet, said burner comprising a jacket having a flame orifice in its lower portion and a direct fuel inlet in its upper portion, and a central part spaced from the jacket by fuel passages surrounding such central part, and an ignition tube arranged at an

angle to the jacket and directing the flame therefrom upon the central part of the burner to heat the latter.

2. A liquid heater comprising a casing open to a liquid supply and having an outlet, a burner arranged in the casing below the outlet, said burner comprising a jacket having a flame orifice in its lower portion and a direct fuel inlet in its upper portion, a central part spaced from the jacket by fuel passages surrounding such central part, an ignition tube arranged at an angle to the jacket and directing the flame therefrom upon the central part of the burner to heat the latter, a fuel pipe leading to the fuel inlet of the burner, and a bypass leading from the fuel pipe to the igniter tube.

3. A liquid heater comprising a casing open to a liquid supply and having an outlet, a burner arranged in the casing below the outlet, said burner comprising a jacket having a flame orifice in its lower portion and a direct fuel inlet in its upper portion, and a central part spaced from the jacket by fuel passages surrounding such central part, and an ignition tube arranged at an angle to the jacket and directing the flame therefrom upon the central part of the burner to heat the latter, the central portion of the burner being formed with an opening extending entirely therefrom and open to the casing at the ends of the burner.

In witness whereof I have hereunto set my hand.

OSCAR ANTON BRUNLER.
